UNITED STATES PATENT OFFICE.

MAUD HENDERSON-BLAND, OF LONDON, ENGLAND.

BUST BODICE.

Application filed March 13, 1922. Serial No. 543,427.

To all whom it may concern:

Be it known that MAUD HENDERSON-BLAND, of 219A Maida Vale, London, W., England, whose post-office address is 219A

5 Maida Vale, London, W., England, has invented certain new and useful Improvements in Bust Bodices, of which the following is a specification.

This invention for an improved bust 10 bodice, has for its object to provide a lady's undergarment for use with or without corsets, that shall conform closely to the natural shape of the body, shall afford adequate support to or control of those parts of the 15 figure which are most subject to excessive development or deformation, and whilst resisting those undesirable involuntary movements or displacements of the figure which are inconsistent with the preservation and 20 maintenance of graceful natural outlines, shall nevertheless freely permit of all necessary voluntary movements of the body and at the same time ensure the maximum of ease and comfort to the wearer.

25 According to this invention the bust bodice which can be worn next the skin or over a thin undergarment for example, is made of any suitable fabric or material and fits exactly to the human figure, the material 30 being so cut and manipulated that some parts of the finished garment are practically inextensible and other parts are capable of stretching to a limited extent to give necessary play to the muscles. The garment 35 is cut full length from the shoulder to the hips and laced up or otherwise secured in front. Each front half is made of one width of material extending from the shoulder to the bottom of the garment and 40 is taken in to fit the figure as hereinafter described from the bottom of the garment to the breast line where a dart is made horizontally, the surplus portion from the waist line to the dart which is of gradually diminishing width from the bottom upwards being folded or laid over and stitched on to the adjacent side portion of the front width, the laid over portion being so cut or shaped 45 that its lower part extends downward and toward the back from upper to lower waist line.

The back is cut in one piece and has a small tuck in the center extending down from the neck to the lower waist line. In 50 order to give free play to the back muscles, portions cut on the cross are inserted in the

back and extend from the bottom over the hip regions to the shoulder blades, where each inserted portion terminates in a point. Parts under the arms and adjacent parts are 60 reinforced or supported by strips of whalebone or other material inserted for the purpose, these underarm parts and adjacent parts fitting closely and preventing the unsightly bulging of muscles under the arms, 65 and over the back of the corset. By shaping the material on natural lines over the bust, pressure upon and unnatural flattening of the breast is avoided.

In some cases, the shoulder pieces of the 70 garment are made detachable and secured by buttoning so that they can be changed for day and evening wear. In other cases elastic webbing is applied over the shoulders and made detachable for washing purposes, 75 and in others the lower part of the bodice has a bifurcated extension and can be used as a bathing costume.

The invention is hereinafter described with reference to the accompanying drawings in which similar reference characters are employed to indicate similar parts throughout the different views.

Figs. 1, 2 and 3 are front, side and back views respectively of a garment made in 80 accordance with this invention.

Figs. 4 to 6 are detail views of the patterns to which the material for the garment is cut.

Figs. 7 and 8 illustrate the application of 90 a detachable elastic webbing to the shoulder.

Fig. 9 is a front view of a modified form of garment adapted for use when bathing.

Fig. 10 is a view similar to Fig. 1 showing a slightly modified form of bust bodice 95 designed to give extra support to the abdomen.

As shown in Figs. 1 to 6 each front half *a* of the bodice is cut with an integral shoulder piece *a'* which extends to the top of the 100 shoulder and is there joined to a corresponding shoulder piece from the back. The line of the bodice round the arm is shaped to hold the muscles under the arm, bones or stiffeners *b* being sewn in the material or otherwise applied below the arm and disposed at suitable angles to give the required support.

The garment, which extends down to the hips is cut full length from the shoulder and laced up or secured in front through eyelet holes or buttons or boot fasteners the bot-

tom part *c* of the lacing being elastic, whilst the remaining part *c'* which extends to the top is of the usual kind.

It will be seen on reference to the pattern

- 5 Fig. 6 that the front half is composed of one width of material and six or more inches from centre front according to size, material is taken in to fit the figure from the bottom of the bodice to the breast line, 10 where a dart *d* is made horizontally. From the bottom upwards the taken in portion is cut and stitched as a straight seam *e* to about $12\frac{1}{2}$ inches from the bottom surplus material being worked into the seam. The 15 remaining surplus portion *f* from the waist line to the dart *d* which is of gradually diminishing width from the bottom upwards is folded or laid over and stitched flat on to the adjacent side portion *g* of the 20 front width, the laid over portion being so cut or shaped as illustrated that its lower part *g'* extends downwards and towards the back from upper to lower waist line terminating in a point from which there is a 25 slight upward slant to the dart. As the joint between the shaped portion *f* and the adjacent side portion *g* of the front runs on the bias or slightly on the cross a certain stretching is permitted to give free play to 30 the muscles at and above the waist. The material of the side portion *g* of the front width, which lies under the shaped overlaid portion *f* and the edge *g''* of which is indicated by a dotted line, is not cut away but 35 is left to support the figure, there being a direct downward continuation of material on the straight from the shoulder to the bottom of the garment where a button holed tab *h* is provided for the attachment of a 40 stocking suspender the pull of which holds the figure in position and prevents it from falling over the corset where such is worn.

The back and shoulder blade part *i* is cut in one piece a portion of gradually diminishing width being cut out from the bottom over the hip region to a point at the shoulder blade and replaced by a correspondingly shaped piece of material *j* cut completely on the cross which gives free play to the 45 back muscles whilst the part *i* holds them firmly in position. Where the back and side front join, a whalebone or stiffener *b'* is inserted which gives firm support to the back. A miniature tuck *z'* is taken down 50 the back from the neck to the low waist line to cause the garment to hold closely and follow the natural contour of the figure.

In order to hold the garment in position, 55 suspenders are attached to tabs *k* at the bottom of the centre front and to tabs *k'* applied preferably where the main front and back seams end, all suspenders having an elastic insertion.

For evening wear the neck opening of the 60 garment is cut to a V-shape at the back or

square or oval as fashion dictates and is cut lower than that shown in front and under the arms with a narrower effect on the shoulder.

Figs. 7 and 8 illustrate the application of 70 elastic webbing *l* over the shoulder which is preferably buttoned on and removable for washing purposes. This modification is made in garments intended to be worn for games and sports where extra freedom of 75 movements is required as for example in playing golf, hockey and other games.

A garment made on the same lines as already described but continued at the bottom in the form of knickers is illustrated in 80 Fig. 9. This garment is intended to be worn under a bathing costume for bathing and is preferably made of waterproof net, with the extremities of the legs drawn in with elastic. In this form the stiffeners under the arms 85 are or may be omitted.

As illustrated in Fig. 10, stiffeners *m* of whalebone or other suitable material indicated by dotted lines, may be applied when required to the parts *a* to give extra support to the abdomen. The center part is also 90 preferably extended as shown at *n* and as it has been found that this extension results in increased comfort apart from the support it affords, it may be used either with the stiffeners *m* or in the forms of bust bodices 95 previously described where the stiffeners *m* are omitted.

I claim,

1. A garment of the character described 100 comprising a rear section having shoulder portions provided with depending tapered extensions, front and side forming sections having their rear edge portions secured to the outer edges of the depending extensions 105 of the rear sections, each of the front and side forming sections being cut from its lower edge to provide a side portion and a front portion with the front portion including a rearwardly extending tongue having 110 its lower end portion tapered downwardly and rearwardly and extending in overlapping relation to the side forming sections when the edges of the two sections are brought together beneath the tongue in overlapping relation, and intermediate sections 115 positioned between the sides of the rear section and rear edges of the attached shoulder extensions and side sections.

2. A garment of the character described 120 comprising a rear section having shoulder portions provided with depending and tapered shoulder extensions, intermediate sections tapered upwardly and secured to the side edges of the back section and depending shoulder extensions thereof, and front and side forming sections each having its upper portion cut to provide arm openings and shoulder-strap forming portions, each forward section being cut from its lower edge 125 130

to provide front and side sections extending in spaced relation and the front section having a rearwardly extending tongue tapered downwardly for extending in overlapping relation to the side sections and providing a triangular reinforcement when the edges of the front and side sections are brought together.

3. The structure of claim 2 having the intermediate sections of the garment formed from material cut on the bias to permit the intermediate sections to have give transversely of the garment when put in place.

4. The structure of claim 2 having the rear section provided with a gathering extending longitudinally of the back from the upper edge thereof and intermediate its width, said gathering extending to a point adjacent the waist line to remove fullness.

5. A garment of the character described comprising a rear section having upwardly extending shoulder strap extensions and having the shoulder portions provided with depending and downwardly tapered exten-

sions, intermediate sections tapered upwardly and sewed to the rear section with their upper end portions extending between the main body of the rear section and the inner edges of the depending shoulder extensions, front sections having their upper portions sewed to the outer edges of the depending shoulder extensions of the rear section from a point slightly above the waist-line, the upper portions of the front sections forming the bust portion of the garment and having their upper ends cut to form arm openings and shoulder strap portions, the front sections being sewed to the forward edges of the intermediate sections below the depending shoulder extensions of the rear section, and the front sections being cut from their lower edges to provide forward and side portions brought together to remove fullness below the bust line and about the waist portion.

In testimony whereof she has affixed her signature, in presence of two witnesses.

MAUD HENDERSON-BLAND.
